(57) **CLAIM**

I claim the ornamental design for a hand forming shuffler, as shown and described.

DESCRIPTION

FIG. 1 shows an isometric front view of the hand forming shuffler mounted on a table.

FIG. 2 shows an isometric front view of the hand forming shuffler.

FIG. 3 shows an isometric rear view of the hand forming shuffler.

FIG. 4 shows a front view of the hand forming shuffler.

FIG. 5 shows a side view of the hand forming shuffler.

FIG. 6 shows rear view of the hand forming shuffler.

FIG. 7 shows top view of the hand forming shuffler; and, FIG. 8 shows bottom view of the hand forming shuffler. In the drawings, the broken lines depict environmental subject matter only and form no part of the claimed design.
